UNITED STATES PATENT OFFICE.

FREDERIC NORWOOD, OF GLOUCESTER, MASSACHUSETTS.

QUICK-ACTING WRENCH.

No. 823,541.

Specification of Letters Patent.

Patented June 19, 1906.

Application filed June 21, 1904. Renewed January 24, 1906. Serial No. 297,612.

To all whom it may concern:

Be it known that I, FREDERIC NORWOOD, a citizen of the United States, residing in Gloucester, in the county of Essex and State 5 of Massachusetts, have invented an Improvement in Quick-Acting Wrenches, of which the following description, in connection with the accompanying drawings, is a specification, like letters on the drawings representing 10 like parts.

This invention relates to a quick-acting wrench, and has for its object to provide a simple and efficient wrench which can be adjusted to the work substantially in an instant. The invention is herein shown as embodied in a monkey-wrench provided with a shank having threaded and non-threaded portions upon which is fitted a movable jaw, and a threaded nut having an enlargement 20 which permits disengagement of the nut from the threaded portions of the shank, and thereby enables the nut and movable jaw to be moved bodily longitudinally on said shank.

25 These and other features of this invention will be pointed out in the claim at the end of this specification.

Figure 1 is a side elevation of one form of wrench embodying this invention; Fig. 2, a 30 cross-section on the line 2 2, Fig. 1, showing the parts in their engaged position; Fig. 3, a cross-section showing the parts in their disengaged position; Fig. 4, an elevation of a modified form of wrench embodying this invention; and Fig. 5, a cross-section on the line 5 5, Fig. 4.

Referring to Figs. 1, 2, and 3, *a* represents the fixed jaw, and *b* the movable jaw, of a wrench embodying this invention.

40 In the construction shown in Fig. 1 the movable jaw *b* is mounted to slide freely on the shank *c*, affixed to the jaw *a*, and is held in its adjusted position by a nut *d*, provided, as herein shown, with an annular flange *e*, 45 which is engaged by inwardly-extended lips or flanges *f*, located substantially diametrically opposite on the jaw *b*. The nut *d* is provided on its interior with screw-threads *g*, which extend about the inner nut for the 50 greater portion of its inner circumference and which are adapted to engage screw-threads *h* on substantially diametrically opposite portions of the shank *c*, which is made substantially oblong in cross-section

and is provided with plain or unthreaded 55 portions or sides *i*, substantially at right angles to the threaded portions. The nut *d* is provided on its interior with an outwardly-extended recess or enlargement *k* of a width substantially equal to the narrower width of 60 the shank, and in the present instance the recess *k* is represented as substantially tapering or converging to receive the narrower edge of the shank *c* when said recess is brought into alignment with the narrower 65 edge of said shank.

In Fig. 2 the nut is shown in the position it occupies when the movable jaw is in its operative position. (Shown in Fig. 1.) If now it is desired to adjust the jaw *b* with relation 70 to the jaw *a*, the nut is partially rotated or turned from the position shown in Fig. 2 into that shown in Fig. 3, and when the recess *k* is brought into line with the narrow side of the shank *c* the said nut is moved laterally 75 with relation to the shank, or vice versa, until the threaded portion on the opposite or wider side of the shank is disengaged from the screw-threads of the nut, whereupon the nut *d* and the jaw *b* connected therewith may be 80 moved bodily toward or away from the fixed jaw and into the desired position, and when brought into such position the nut is moved laterally in the opposite direction to again engage the threads on the rear side of the 85 shank, after which the said nut may be turned to remove the recess from in line with the threaded front side of the shank. Further movement of the jaw *b* toward the fixed jaw may be effected by rotating the nut in 90 the usual manner, which is permitted by the rear edge of the shank being wider than the recess *k* in the nut.

In Fig. 1 I have represented the movable jaw as separate from the nut *d*; but, if desired, said jaw and nut may be made in one piece, as represented in Figs. 4 and 5. So, also, the fixed jaw *a* may be integral with the shank, as represented in Fig. 1, or it may be separate therefrom and secured thereon by a 100 pin *m*, the said jaw resting against a shoulder *n* on said shank *c*. The wrench may be provided with a suitable handle *o*.

From the above description it will be seen 105 that the movable jaw may be quickly adjusted toward or from the fixed jaw by a rotary movement, followed by a bodily movement longitudinally of the shank and inde-

pendent of said rotary movement, and that such adjustment may be made substantially in an instant.

I claim—

5 In a wrench of the class described, in combination, a fixed jaw, a shank having a narrow front edge and a wider rear edge provided with threads, a movable jaw, and a nut threaded on its interior to engage the
10 threads of said shank and provided with a recess of a width sufficient to receive the nar-

row threaded edge of said shank and not sufficient to receive the wider threaded edge of said shank, for the purpose specified.

In testimony whereof I have signed my ¹⁵ name to this specification in the presence of two subscribing witnesses.

FREDERIC NORWOOD.
